UNITED STATES PATENT OFFICE.

BERTRAM CORBETT GARMAN, OF WEST HAMPSTEAD, LONDON, AND CHARLES OLIVER,
OF CHISLEHURST, ENGLAND, ASSIGNORS TO OLIVER PELL CONTROL LIMITED,
OF WOOLWICH, ENGLAND, A BRITISH LIMITED LIABILITY COMPANY.

STEP-BY-STEP ROTARY ELECTRIC SWITCH.

Application filed February 12, 1926, Serial No. 87,886, and in Great Britain July 17, 1925.

This invention relates to step-by-step rotary electric switches of the rapid make and break type embodying a number of fixed contacts spaced apart, usually at equal angular intervals, around a central operating spindle, with series of rotating contacts actuated by said spindle and adapted to be moved into and out of engagement with said fixed contacts to close or open one or more electrical circuits.

An object of the present invention is to provide a rotary switch of this type capable of giving a wider variation of circuit control without undue complication or multiplication of parts. For instance in modern electric heating and cooking stoves it is desirable to have more than three temperature changes, which is the number now usually employed, and it is to the provision of a simplified and practical form of rotary switch capable of giving this improved temperature grading, that our present invention is primarily directed.

The connections required to give three temperature changes are readily obtainable in a switch with four "points" or angular switching positions which include a single "off" position. When it is attempted however to provide more than three heating positions, the switch becomes complicated.

For example, in a known form of switch adapted to give four separate heating positions two "off" positions are employed so that the switch of necessity has six "points" or angular switching positions.

In the improved switch of the present invention, more than three electrical circuit connections and a single "off" position are obtained by the employment of a number of "points" or angular switching positions equal only to the number of circuit connections plus the one "off" position.

More particularly the switch of the present invention embodies a plurality of fixed terminals disposed about a central operating spindle, two series of rotating contacts insulated from each other and spaced apart in the lengthwise direction of said operating spindle to engage with correspondingly spaced fixed contacts on the terminals, a plurality of additional rotating contacts disposed intermediate—or external to—the two series of rotating contacts and electrically connected to one or other of them, and one

or more intermediate—or external—fixed contacts on the terminals to receive the additional rotating contacts in certain angular positions of the rotating contacts. By "external" is meant above or below the ordinary series of contacts in the lengthwise direction of the operating spindle.

The switch of the present invention may advantageously be constructed as a double pole switch. The accompanying drawings illustrate a double pole reversible switch in accordance with the present invention adapted to give four separate circuit connections corresponding to separate temperature grades, and one "off" position.

In these drawings:—

Fig. 1 is a central sectional view of the switch, with the cover removed.

Figs. 2 to 6 are developed diagrams of the switch contacts and connections corresponding respectively to the "off" and the four progressive working positions.

Referring more particularly to Fig. 1:—

The switch comprises the usual insulating base A, operating spindle B and indicating knob C. The arrangements for making the switch reversible i. e. rotatable in either direction, are described in the specification of Oliver's co-pending patent application filed U. S. A. Feb. 8, 1926 Serial Number 86,899. Shortly, this reversing arrangement comprises a number of fixed abutments M arranged in pairs corresponding to the number of switching positions, one abutment of each pair being set above and the other below the central position of a pawl N which embraces the spindle B and is raised or lowered by a spiral groove O so as to escape one or other of the abutments M, when the spindle B is turned in either direction.

Mounted on the base A are five fixed terminals D¹, D², D³, D⁴ and D⁵ carrying contact clips or brushes E of the known kind. Free on the spindle B is a rotative contact carrying member F connected to the spindle B through the driving spring G in the manner described in Oliver's said specification Ser. No. 86,899. Fixed to the contact carrying member F are two series of rotating contact blades arranged at top and bottom and denoted respectively by H and J. The blades H project from a metallic plate H¹ and the blades J from a plate J¹, the

two plates being insulated from each other.

In electrical connection with the plate H^1 is a plate K^1 having a single projecting blade K , and in electrical connection with

- 5 the bottom plate J^1 is a plate L^1 carrying two projecting blades L , one of which latter is in the vertical group of blades next adjacent to the blade K in the clockwise direction round the switch, and the other blade
 10 L is two groups further removed in the same direction. The top series of contacts H with contact K are adapted to make the terminals 3 and 5 (see Figs. 2 to 6) live to one pole of the circuit through terminal
 15 2 which is one line terminal and the bottom series J with contacts L are adapted to make terminals 1 and 5 live to the other pole of the circuit, through terminal 4 which is the other line terminal.
 20 One of the fixed terminals D carries a brush in an intermediate position such that it will receive the blades K or L in certain angular positions of the switch.

Referring now to Figs. 2 to 6:—

- 25 The fixed terminals are numbered 1 to 5 in a counter-clockwise direction, and in order more clearly to explain the action of the switch it is shown applied to the control of two resistances X and Y , of which Y is
 30 greater than X , forming heating elements, for instance in an electric stove or heater.

Now in order to obtain with these two elements four separate degrees of heat they must be connected:—

- 35 (1) Both in series (lowest heat).
 (2) Smaller one singly.
 (3) Larger one singly.
 (4) Both in parallel (highest heat).

- The terminals 2 and 4 are the external
 40 line terminals, the resistance Y is connected across terminals 1 and 3, and the resistance X across 3 and 5.

Fig. 2 shows the "off" position in which the terminals 2 and 4 are not engaged.

- 45 Fig. 3 shows the first heat position in which the resistances X and Y are connected in series, the line terminal 2 being connected by a top blade H to the terminal 5 which engages the intermediate blade K ,
 50 the latter, as above described being in an electrical connection with the whole top series of blades H . The terminal 1 is connected to the terminal 4 by bottom blades J .

- Fig. 4 shows the second heat position employing the resistance X only, terminal 2 being connected to 3 by top blades H , and 4 to 5 by a bottom blade J and intermediate blade L in connection with the bottom series.

- 60 Fig. 5 is the third heat position employing resistance Y alone, terminal 2 being connected to 3 by top blades H , and 1 to 4 by bottom blades J .

- 65 Fig. 6 shows the fourth and highest heat position in which resistances X and Y are

connected in parallel, terminal 2 being connected to 3 by top blades H , and 1, 3 and 4 by bottom blades J and intermediate blade L .

In this manner the present invention provides a reversible rotary switch having four working positions and in which the number of "points" or angular switching positions does not exceed the number of working positions plus a single "off" position. 70 75

In an alternative construction according to the present invention, the additional contact blade K may be arranged above the blades H , or/and the blades L below the blades J , instead of the intermediate arrangement of blades K and L above described. 80

In this case, two correspondingly disposed contact clips or brushes would be provided on the terminals 5. 85

It is to be understood that the invention is not limited in its application to reversible switches of any type or to any particular form of operating mechanism but may equally well be applied to unidirectional rotary switches with any suitable form of operating mechanism so long as it is of the rapid make and break type. 90

What we claim is:—

1. A rapid make and break rotary electric switch embodying a plurality of fixed terminals disposed about a central operating spindle, two series of rotating contacts insulated from each other and spaced apart in the lengthwise direction of said spindle to engage with correspondingly spaced fixed contacts on the terminals, a plurality of additional rotating contacts disposed in different angular positions around the switch in planes other than those of the two series of rotating contacts and electrically connected to one or other of said series, and one or more additional fixed contacts to receive the additional rotating contacts in a certain angular position or positions of the switch. 100 105 110

2. A rapid make and break rotary electric switch in accordance with claim 1 in which the additional rotating and fixed contacts are all disposed in one plane which is intermediate the planes of the two usual series of contacts. 115

3. A rapid make and break rotary switch in accordance with claim 1 in which the additional rotating and fixed contacts are external to the usual series of contacts. 120

4. A rapid make and break rotary switch adapted to provide four working positions and a single "off" position with five fixed terminals and five angular switching positions only, comprising two series of rotating contacts of opposite polarity with suitable fixed terminal contacts to receive them, an additional rotating contact in electrical connection with one of said series of rotating contacts, two additional rotating contacts 125 130

electrically connected to the other said series, all of said additional rotating contacts being in different angular positions around the switch and in planes other than those of the 5 two series of rotating contacts and one or more additional fixed contacts carried on one of the fixed terminals and appropriately placed thereon to receive the additional rotating contacts in certain switching positions.

10 5. A rapid make and break rotary switch comprising a plurality of fixed terminals disposed about a central operating spindle which is rotatable in either direction, two 15 series of rotating contacts insulated from each other and carried by a rotating contact-carrying member with a spring interposed between the spindle and said contact-carrying member, a plurality of fixed contacts to 20 receive the rotating contacts, a plurality of additional rotating contacts disposed in different angular positions on the contact-carrying member in planes other than those

of the two series of rotating contacts and electrically connected to one or other of said series, one or more additional fixed contacts to receive the additional rotating contacts in a certain angular position or positions of the contact-carrying member, two series of abutments disposed about the operating 30 spindle, and a pawl normally engaging with a pair of said abutments and thereby holding said contact-carrying member against rotation in either direction, the operation being such that rotation of the spindle in either direction stresses the spring and produces a relative movement lengthwise of the spindle between the pawl and the abutments until disengagement takes place, whereupon the contact-carrying member is rotated by 35 said spring until the pawl becomes engaged by the next abutment of the series which opposes rotation in that direction. 40
